ORNAMENT AND METHOD OF MAKING THE
SAME

Magda Baumstark, Chicago, Ill.

Application October 20, 1939, Serial No. 300,287

7 Claims. (Cl. 41—10)

The invention relates to ornaments and to the method of making the same, and more particularly to the manufacture of artificial flowers or the like, composed of petals formed by winding and sewing strands of suitable material upon a removable mandrel.

An object of the invention is to provide attractive ornaments which comprise the joining together of a plurality of individual units each formed by winding a strand of material upon a mandrel.

Another object of the invention is to provide attractive ornaments which can be manufactured easily and inexpensively.

Another object of the invention resides in the provision of novel steps in the method of manufacturing artificial flowers.

Another object of the invention is to provide a winding tool adapted for forming individual units of various sizes.

The foregoing and such other objects of the invention as will appear hereinafter as the description proceeds will be more readily understood from a perusal of the following specification; in which reference is made to the accompanying drawing, wherein:

Fig. 1 is an elevational view of the winding tool showing a strand of material in its initial stage of winding.

Fig. 2 is a fragmentary view similar to Fig. 1, showing a step in the method of winding to form a petal, with the loops separated for the purpose of illustration.

Fig. 3 is a fragmentary view similar to Fig. 2, illustrating the next step in the making of a petal, and showing the loops pushed together.

Fig. 4 is a view similar to Fig. 3, showing the loops sewed together.

Fig. 5 is a view of a completed part.

Fig. 6 is an elevational view showing the part of Fig. 5 pressed flat.

Fig. 7 is a perspective view showing the first step in the assembling of a flower.

Fig. 8 shows a second step in forming a flower.

Fig. 9 is a perspective view of a completed flower.

Any suitable loosely woven fine yarn preferably is used in carrying out the invention although it is to be understood that the invention is not limited to such a yarn, but may be readily carried out with a strand or strands of other material, the selection of which is determined by choice.

As best shown in Fig. 1, a suitable winding tool consisting of a handle 11 and a flat mandrel 12 preferably is used. As shown, the mandrel

12 may be slotted at one end for ready association with the handle 11. It is obvious that mandrels of varying widths may be employed, the determination of the width being governed by the size of the article to be made.

The winding end 13 of the strand of material S is first looped tightly over the mandrel as illustrated at 14 in Fig. 1 and the tool is then twisted to make two turns 15 about the starting or holding end 16 of the strand. The winding end 13 10 is then looped around the mandrel to form a second loop 14a (Fig. 2) and then is twisted once around the holding end 16, as at 17. This looping and twisting is repeated, as illustrated in Fig. 2, until the desired number of loops 14b, 14c, etc.; 15 are made. The free ends of the holding strand 16 and winding strand 13 then are carried upwardly around the mandrel 12, tied, and then threaded through a needle 18.

During the winding and twisting process the 20 strands are, of course, pulled tightly and pressed closely together as best illustrated in Fig. 3. The needle 18 is then worked through the upper free ends of the loops 14, etc., to form an unbroken series of stitches 19 as shown in Fig. 4. In that 25 manner the free ends of the loops are securely sewed together at the end opposite the end joined by the twisting of the strand. The free ends 13 and 16 of the strand are then cut off and the completed part 21 is removed from the mandrel 30 as shown in Fig. 5. It is obvious that the individual loops, etc., are securely joined together on the lower end of the part 21 by the twistings 15 and 17 and on its upper end by the stitches 19.

After a part has been pressed substantially into 35 the shape of a petal as illustrated in Fig. 6, it is coiled loosely and the stitched end is drawn together tightly by sewing, as shown in Fig. 7, around one end of a stem wire 22. Additional petals 21a, 21b, etc.; are added by successively 40 coiling them loosely about the initially attached petal 21. It will be noted upon viewing Figures 8 and 9 that the complementary ends of the petals overlap each other slightly and that any desired number of petals may be added to form, for example, the rose 23. After the desired number of petals are securely sewed in place, a cup 24 is slipped over the wire and urged over the sewed edges of the petals to conceal the stitches and complete the flower. The wire 22 is then wrapped 45 in the customary manner with a strip of material 25 thereby completing the ornament. Stems 26 may be attached while wrapping.

It is apparent from the foregoing that a realistic looking flower is produced efficiently, quickly and 55

economically and that the manufacture of such a flower requires no experience, but may be readily accomplished by any person having but slight knowledge of needlework. It should also be understood that each petal 21 retains its shape and position in the assembled ornament due, in part at least, to its firm anchorage to the stem 24 and further to the relatively firm upper margin formed by twisting the end portions 13 and 16 while winding the strand.

Obviously the stitching together of the loose ends of the loops retain said loops in their closely adjacent positions assumed during the winding as distinguished from the known practice of tying, which obviously draws said loops tightly together in a bunch. Consequently, distortion of the desirable flatness of the petal is avoided.

Although an exemplary ornament is illustrated and the specific steps taken in its manufacture are described, it is to be understood that the disclosure is illustrative only and not restrictive or that the invention is not to be limited to the precise disclosure but is to embrace such modifications as may fall within the spirit of the invention and the scope of the appended claims.

I claim:

1. In the manufacture of an ornament the steps, which consist of, looping one end portion of a strand around a mandrel, twisting said end portion around the other end portion of said strand, making a plurality of loops around said mandrel and twisting the two end portions together after the completion of each loop, and finally stitching the free ends of said loops together.

2. In the manufacture of an ornament the steps, which consist of, looping one end portion of a strand around a substantially flat mandrel, twisting said end portion around the other end portion of said strand at one edge of said mandrel, making a plurality of loops around said mandrel and twisting the two end portions together on said edge of the mandrel after the completion of each loop, and finally stitching the

loops together adjacent the other edge of said mandrel and then withdrawing said mandrel.

3. The herein described method including the steps of looping an end portion of a strand around a form in one direction, twisting said portion around the other end portion of said strand in a reverse direction along one edge of said form, repeating the looping and twisting of said portions to provide a plurality of closely associated loops joined together at one edge of said form, and finally sewing said loops together at the opposite edge of said form.

4. The method of making ornaments, consisting in holding a strand of material at one end against a mandrel, looping one end of said strand around the mandrel and twisting it around the end being held, looping the strand repeatedly around said mandrel, twisting said strand around the end being held after making each loop to anchor one end of each of said loops, stitching together the free ends of said loops with both free end portions of said strand, said stitching securing the free ends of said loops in a substantially flat plan, and finally removing said joined loops from the mandrel and pressing.

5. An ornament comprising a strand having one end portion defining a plurality of loops; the strand defining each of said loops being twisted around the other end portion of said strand to secure the loops together at one end, and the free ends of said loops being stitched together by both free end portions of said strand.

6. An ornament comprising a plurality of separate parts sewed together, each of said parts consisting of a substantially flat element formed of loops of material, said loops being joined at one edge of said part by twisting the material and at the opposite edge by sewing.

7. An element adapted to constitute a part of an ornament consisting of a plurality of loops of a single strand of material, said loops being secured together at one edge of said unit by twisting and at the other edge by sewing.

MAGDA BAUMSTARK.
